(57) **CLAIM**

The ornamental design for closure tabs for a container, as shown and described.

DESCRIPTION

FIG. 1 is a perspective view of a first variant of a design of closure tabs in an open state before having been closed;

FIG. 2 is a perspective view of the first variant of the design of FIG. 1, showing the closure tabs in a fully closed state;

FIG. 3 is a perspective view of the first variant of the design of FIG. 1, showing the closure tabs in an open state after having been closed; and,

FIGS. 4, 5 and 6 are perspective views of a second variant of the design in states corresponding respectively to the views of FIG. 1, 2, and 3.

In the figures, the features shown in broken line are for environmental purposes and form no part of the claimed subject.
